UNITED STATES PATENT OFFICE.

JOHN F. PETERS, OF ROCHESTER, NEW YORK, ASSIGNOR TO AMERICAN CAN COMPANY, OF NEW YORK, N. Y., A CORPORATION OF NEW JERSEY.

MACHINE FOR SCORING AND FORMING TAPERED CANS.

Application filed February 13, 1925. Serial No. 8,900.

My invention relates to can making machinery and has for its main object the provision of a machine for automatically feeding and scoring arcuate blanks, such as are employed in the making of tapered can bodies. Cans of this type are used for various food products, such as plum pudding, canned chicken and some kinds of potted meats, and due to the particular manufacturing difficulties presented by the arcuate form of the blanks, it has heretofore been customary to make such cans largely by hand operations.

The scoring operations for forming a tearing strip in the body of the can have, in the past, been performed one at a time, the blanks being transferred from one scoring unit to another by hand and the scored blank thereafter transferred to forming rolls and the mechanism for forming and bumping the side seam.

The purpose of my invention is to provide a scoring machine in which the blanks are automatically propelled from one station to another and a plurality of scoring operations successively performed thereon by automatic mechanism, thus eliminating the relatively slow hand method heretofore employed and greatly increasing the efficiency and rate of production.

It is also an object of the invention to provide an automatic machine which includes forming rollers adapted to accurately shape the blank after the scoring operations have been completed, thus facilitating subsequent handling and feeding of said blank through the bodymaker.

Numerous other objects and advantages of the invention will be apparent as it is better understood from the following description, which, taken in connection with the accompanying drawings, discloses a preferred embodiment thereof.

Referring to the drawings,

Figure 1 is a top plan view of a machine in which my invention is embodied, a part thereof being broken away to more clearly illustrate the mechanism;

Fig. 2 is a front elevation of the machine, certain parts being shown in section;

Fig. 3 is an end elevation, taken from

the right in Fig. 2, part of the frame being shown in section to illustrate the driving mechanism for the scoring rolls;

Fig. 4 is a sectional view, taken substantially along the section line 4-4 in Fig. 1;

Fig. 5 is a detail sectional view, taken upon the section line 5-5 in Fig. 1; and

Fig. 6 is a perspective view of the completely scored and formed blank, illustrating the results of the several operations performed by the machine.

As thus illustrated, the machine comprises a frame, consisting of a table or bed plate 11, supported at three sides by legs 12, two of which are connected by tie rods 13, the various parts of the operating mechanism being mounted upon said frame and arranged to perform a plurality of successive operations upon the can body blank as the latter is automatically propelled through the machine.

A drive shaft 14 is journaled in bearings provided in the upper ends of the legs 12 and in a bearing 15 depending from the bottom of the bed plate 11, said shaft 14 carrying a pulley 16 at one end thereof adapted to be driven from any suitable source of power.

A segmental disk 17 is mounted upon a stud 18, secured within a post or tubular bracket 19, extending upwardly from the bed plate 11, said stud 18 being held in fixed relation by means of a set screw 21. A circular track for the blanks is provided between guide rails 22 and 23 upon the upper surface of the disk 17. The blanks, which I have indicated by the reference character 24, are adapted to be placed between said guide rails, either by hand or by any suitable feeding mechanism, and are first acted upon by a scoring unit, which is shown particularly in Figs. 1 and 2 of the drawings. A scoring roller 25, having cutting edges 26 upon its periphery, is carried upon a shaft 27, which is journaled in a bearing box 28 secured in an overhanging part of a bracket 29 which is supported upon and extends upwardly from the table 11. A feeding roller 31 is mounted beneath the scoring roller 25 and extends through an opening 32 in the disk 17 so that the blank

100

may be engaged between said rollers for feeding and scoring. Said roller 31 is secured to a shaft 33, journaled in a bearing box 34 upon the bracket 29, said bracket being cut away, as indicated at 35, in order that said bearing boxes 28 and 34 may be supported in spaced parallel relationship above and below the circular track upon the disk 17. The roller shafts 27 and 33 have tongue and groove connections, respectively, with shafts 36 and 37 which are journaled in the bracket 29 and carry at their outer ends meshing gears 38 and 39 whereby the rollers are driven in unison by power from the shaft 14 transmitted by a chain 41, taking over sprockets 42 and 43 mounted respectively upon said shaft 14 and the shaft 37. The details of construction of this scoring unit, as well as of the other unit shown in the present embodiment of the invention and to be later described, are clearly disclosed in my pending application Serial No. 685,628, filed January 11, 1924.

The blanks, after having parallel score lines 44 and 45 formed therein by the mechanism just described, are engaged by feeding rollers 46 and 47 at the next station in the machine, the mechanism at this station being best shown in Figs. 1 and 4 of the drawings. The roller 47 is mounted upon a shaft 48, journaled in bearings 49 formed in brackets 51 extending upwardly from the table 11, and the upper roller 46 is idly mounted upon a stud 52 carried by the bracket 51 at the upper end thereof. The shaft 48 is adapted to be driven by means of a belt 53 taking over a pulley 54 upon said shaft and a pulley 55 mounted upon a shaft 56, which is journaled in bearings 57 and 58 depending from the table 11 and carries at its inner end a beveled gear 59, meshing with a gear 61 upon a shaft 62, which carries at its inner end a beveled gear 63, meshing with a gear 64 upon the drive shaft 14.

The feeding unit just described transfers the blanks, from first scoring unit, supported by the bracket 29, to a second scoring unit which is supported in a similar bracket, indicated by the reference character 65. This scoring unit is substantially identical with the one already described and comprises a scoring roll 66, which is provided with cutting edges 67 adapted to form herringbone score lines 68 upon the blank between the parallel score lines 44 and 45, said roller being mounted upon a shaft 69, journaled in a bearing box 71 supported by the bracket 65 and a feeding roller 72 being mounted beneath said scoring roller 66 and carried upon a shaft 73, journaled in a bearing box 74, the shafts 69 and 73 being connected with shafts 75 and 76 carrying meshing gears 77 and 78. The shaft 75 is driven by means of a chain 79, taking over sprockets 81 and 82 mounted respectively upon said

shaft 75 and the shaft 62 hereinbefore referred to, which shaft is journaled in bearings 83 and 84 in the frame.

The next station of the machine is a feeding station, the mechanism at this station being similar to that at the first feeding station, as shown in Fig. 4 of the drawings and already described. The feeding rollers at this station are indicated by the reference characters 85 and 86, and are mounted respectively upon a stud 87 and a shaft 88, journaled in bracket arms 89 extending upwardly from the table, said shaft 88 being driven by means of a belt 91, taking over a pulley 92 upon said shaft 88 and over a pulley 93 upon a shaft 94, which is journaled in bearings 95 and 96 depending from the under side of the table 11, said shaft carrying at its inner end a beveled gear 97, meshing with the gear 61 upon the shaft 62, said feeding rollers being thus driven from the power shaft 14, which drives said shaft 62, through the medium of the inter-meshing gears 63 and 64.

The blank is next delivered to a forming station, which is shown in detail in Fig. 5 of the drawings. At this station, the blanks are fed between forming rollers 98 and 99, which are carried by shafts 101 and 102 journaled in a bearing box 103, the shaft 102 carrying at its outer end a pulley 104 over which is directed a belt 105, taking over a pulley 106 upon the end of a shaft 107 of a motor 108, which is mounted in brackets 109 projecting upwardly from the top of the table 11, this separate drive permitting rotation of the rollers 98 and 99 at greater speed than the scoring and feeding rollers hereinbefore described. As the blank is directed between the rollers 98 and 99, it impinges against a forming plate 111, which is curved at its forward end and adapted to bend the blank upwardly, as shown in Fig. 5. A supporting plate 112 is secured to the bracket 103 just beyond the rollers 98 and 99 and the blanks 24 are arranged over said plate after passing through the forming rolls. They may thereafter be removed by hand, or by any suitable mechanism, the succeeding blanks being arranged one upon the other until there is a sufficient accumulation for removal.

By the described mechanism, the arcuate blanks are automatically propelled through the machine and the necessary scoring operations rapidly and efficiently performed to provide a tearing strip, indicated in Figs. 1 and 6 of the drawings by the reference character 113, this strip, in the present instance, being of the herringbone type which insures the return of the line of tear to the parallel score lines 44 and 45 in the event that it should, for any cause, be deflected therefrom. The blank is bent by the rollers 98 and 99 to cause it to assume the form

shown in Fig. 6 of the drawings, the edges thereof being thereafter interengaged and secured together in the well-known lock and lap seam by any mechanism suitable for this purpose.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages, the form hereinbefore described being merely a preferred embodiment thereof.

I claim:

1. A scoring machine, comprising a support provided with an arcuate track for guiding tapered can body blanks, and a plurality of scoring and feeding elements arranged about said track for automatically moving the blanks through the machine and scoring the same to provide a body tearing strip for opening the can.

2. A scoring machine, comprising a support provided with an arcuate track for guiding tapered can body blanks, a plurality of scoring and feeding elements arranged about said track for automatically moving the blanks through the machine and scoring the same to provide a body tearing strip for opening the can, and means for automatically shaping the blank after it is scored.

3. A scoring machine, comprising a support provided with an arcuate track for guiding tapered can body blanks, a plurality of scoring and feeding elements arranged about said track for automatically moving the blanks through the machine and scoring the same to provide a body tearing strip for opening the can, and means for automatically shaping the blank after it is scored, said means being adapted to operate at higher speed than said scoring and feeding elements.

4. A scoring machine, comprising a support provided with an arcuate track for guiding tapered can body blanks, and a plurality of scoring and feeding elements arranged about said track for automatically moving the blanks through the machine and scoring the same to provide a body tearing strip for opening the can, said scoring and feeding elements comprising a plurality of units each including a scoring roll.

5. A scoring machine, comprising a support provided with an arcuate track for guiding tapered can body blanks, and a plurality of scoring and feeding elements arranged about said track for automatically moving the blanks through the machine and scoring the same to provide a body tearing strip for opening the can, said scoring and feeding elements comprising a plurality of

units each including a scoring roll and feeding means between said scoring units.

6. A scoring machine, comprising a support provided with an arcuate track for guiding tapered can body blanks, a plurality of scoring and feeding elements arranged about said track for automatically moving the blanks through the machine and scoring the same to provide a body tearing strip for opening the can, and means for automatically shaping the blank after it is scored, said scoring and feeding elements comprising a plurality of units each including a scoring roll and feeding means between said scoring units and between the last scoring unit and said shaping means.

7. A scoring machine, comprising a frame including a support, means on said support for guiding blanks of arcuate form adapted for use in making tapered can bodies, and means for automatically propelling said blanks through the machine and performing a plurality of scoring operations thereon.

8. A scoring machine, comprising a frame including a support, means on said support for guiding blanks of arcuate form adapted for use in making tapered can bodies, means for automatically propelling said blanks through the machine and performing a plurality of scoring operations thereon, and means for shaping the scored blanks to substantially the can form.

9. A scoring machine, comprising a frame having an arcuate track mounted thereon, a scoring unit adapted to operate upon blanks in said track, a feeding unit adapted to engage the blanks as they pass from said scoring unit and propel them further along said track, and a second scoring unit adapted to receive the blanks from said feeding unit and perform a second scoring operation thereon.

10. A scoring machine, comprising a frame having an arcuate track mounted thereon, a scoring unit adapted to operate upon blanks in said track, a feeding unit adapted to engage the blanks as they pass from said scoring unit and propel them further along said track, a second scoring unit adapted to receive the blanks from said feeding unit and perform a second scoring operation thereon, and a second feeding unit arranged beyond said second scoring unit.

11. A scoring machine, comprising a frame having an arcuate track mounted thereon, a scoring unit adapted to operate upon blanks in said track, a feeding unit adapted to engage the blanks as they pass from said scoring unit and propel them further along said track, a second scoring unit adapted to receive the blanks from said feeding unit and perform a second scoring operation thereon, a second feeding unit arranged beyond said second scoring unit, and

a forming unit adapted to receive the blanks from said second feeding unit and shape them to substantially the can form.

12. A scoring machine, comprising a frame having an arcuate track mounted thereon, a scoring unit adapted to operate upon blanks in said track, a feeding unit adapted to engage the blanks as they pass from said scoring unit and propel them further along said track, a second scoring unit adapted to receive the blanks from said feeding unit and perform a second scoring operation thereon, a second feeding unit arranged beyond said second scoring unit, and a forming unit adapted to receive the blanks from said second feeding unit and shape them to substantially the can form, said scoring and feeding units being driven from a common source of power and said forming unit having a separate drive.

13. A scoring machine, comprising a support provided with an arcuate track for guiding tapered can body blanks, a plurality of scoring and feeding elements arranged about said track for automatically moving the blanks through the machine and scoring the same to provide a body tearing strip for opening the can, and means including co-

operating rollers and a forming plate against which the blanks are adapted to impinge for automatically shaping said blanks after they are scored.

14. A scoring machine, comprising a support provided with an arcuate track for guiding tapered can body blanks, a plurality of scoring and feeding elements arranged about said track for automatically moving the blanks through the machine and scoring the same to provide a body tearing strip for opening the can, means for automatically shaping the blank after it is scored, and a supporting plate for the blanks beyond said shaping means.

15. A scoring machine, comprising a support provided with an arcuate track for guiding tapered can body blanks, a plurality of scoring and feeding elements arranged about said track for automatically moving the blanks through the machine and scoring the same to provide a body tearing strip for opening the can, means for automatically shaping the blank after it is scored, and a vertical supporting plate adapted to receive an accumulation of scored and shaped blanks.

JOHN F. PETERS.
